UNITED STATES PATENT OFFICE.

HENRY BANG, OF CHICAGO, ILLINOIS, ASSIGNOR OF TWO-FIFTHS TO THEODORE CARSTENSEN, OF CHICAGO, ILLINOIS.

FREIGHT-CAR DOOR.

Application filed September 10, 1924. Serial No. 736,889.

This invention relates to freight car doors, and especially to grain doors for box cars. The main objects of the invention are to provide an improved form of doorway closure means for cars used in handling grain; to provide a grain door of improved construction, adapted for ready manipulation and adjustment to accommodate loading and unloading; and to provide a door member of this character adapted for either sectional operation, or opening as a whole.

An illustrative embodiment of this invention is shown by the accompanying drawings, in which:—

Figure 1 is mainly a perspective view of the front side of a box car showing the doorway in nearly front elevation, the left half of the door being closed and the right half being open.

Fig. 2 is a front elevation of the upper part of the doorway on a reduced scale showing the lower part of the door mechanism closed and the upper part open.

Fig. 3 is a front elevation on the same scale as Fig. 2 showing the lower part of the doorway and door mechanism closed.

Fig. 4 is a vertical section on the line 4—4 of Fig. 1.

In the construction shown in the drawings, the grain carrying box car 1 is provided with a lateral doorway 2 having an outside door 3 hung on trucks 4 for sliding edgewise on the outside of the car as usual for side doors. In order to hold the grain independently of the outside door 3, and to facilitate loading and unloading the car, a supplementary door 5 of novel construction and operation is hinged on the door frame 6, inside of the car, in slightly spaced relation to said door 3, and arranged to swing inwardly for opening.

The grain door 5 comprises substantially a pair of similar right and left sections or halves, each hinged on vertical edge axes to the adjacent door posts 6 respectively as at 7. The inner edges overlap slightly and are provided with fastenings, three being here shown, each including a hasp 8 secured to one section, an eye piece 9 secured to the opposite section and a pin 10 to lock said parts together, said pin having a chain 11 to hold it adjacent to the eye piece when not in use.

Each half of the grain door comprises a plurality of sections, three in this instance,

disposed one above another including a main section 12 disposed medially, a top section 13 adapted to operate independently of the medial section and a bottom section 14 also adapted to be opened and closed independently of the middle section. The middle section 12 is provided with three hinges 7 and two hasps 8. The top section 13 has two hinges 7 and one hasp 8. The bottom section 14 instead of being hinged to the side post is adapted and arranged to be detachably connected to the medial section alternately in either of two positions. When the door is closed, the bottom section is dropped down into place, the lower edge fitting in a groove 14' in the door-sill 1' and the outer side edge fitting between the medial section and the side post 6, a fastener 15 being provided to secure same in place. The fastener 15 is in the form of a bolt having a head 15' formed to serve as a depending handle when in place. The sections 14 and right section 12 are perforated to receive the bolt and section 12 is threaded to engage the bolt tip. This bolt is secured against loss by the chain 15" secured to the left section 14.

When a car equipped with a grain door such as herein described is to be loaded the medial sections 12 are closed first, the left hand part which is closed first overlapping on the outer side the adjacent edge of the right hand part as at 19, where it is secured by the said fasteners. The lower sections 14 are then slipped down into place and secured by the fastening means 15 at their upper inner corners. Finally the upper sections are left open or are swung open inwardly, whereupon the grain may be loaded through the opening thus provided in the upper part of the doorway. After the car is loaded the upper sections may be swung together and locked by means of the hasp 8 on the left section and eye-piece and pin on the right hand section. Both of these top sections 13 overlap the inner side medial sections 12 and the left section which is closed first overlaps on the outside the right section. Moreover, a fastener 21 is provided on the right hand section near its lower edge for engaging the medial section 12 on that side, said fastener being provided in the form of a turn button, one arm of which is made long and is offset to swing downward and

out over the top edge of section 12. The doors when thus closed are very securely held and present a rigid construction.

When the car is to be unloaded, the fastener 15 at the upper inner corners of the lower sections 14 is unscrewed, thus releasing said sections which may then be lifted upward by the handles 22 out of their lower edge frame grooves 14' and hung on the hooks 23 on the middle sections respectively, the sections 14 being apertured at 24 to receive said hooks. This permits the grain to run out by gravity, except that which occupies the lower part of the car, and that may be scraped, shoveled or otherwise forced out through this lower part of the doorway. The lower sections are then removed from said hooks and lowered into place where they are again secured by said fastener 15 and the car is ready to receive another load.

This grain door is of simple and inexpensive construction, is easy to operate, and can be used readily by unskilled labor. It is designed to take the place of the more expensive and more complicated doors occasionally used, as well also as the common crude and rough board closures now used very extensively.

Although but one specific embodiment of this invention has been herein shown and described, it will be understood that numerous details of the construction shown may be altered or omitted without departing from the spirit of this invention as defined by the following claims:

I claim—

1. In a railway car a grain door formed and adapted to swing inward substantially and in effect as two sections hinged to the

sides of the doorway respectively, each of said sections including a medial part and top and bottom parts each movable relative to the medial part, all of said sections being formed and arranged to overlap along their several mutually adjacent edges and the two bottom sections being slidable vertically for opening and closing.

2. In a railway car a grain door formed and adapted to swing inward substantially as two sections hinged to the sides of the doorway respectively, each of said sections including a medial part and top and bottom parts each of said top and bottom parts being adapted to open and close relative to said medial part and independently of each other, all of said sections being made thin and formed of sheet metal and all being arranged to overlap along their several mutually adjacent edges and the lowermost sections being movable edgewise vertically for opening and closing.

3. A six part grain door adapted as a whole to swing open inwardly, said door comprising independently operable right and left halves, each as a whole mounted on hinges to swing laterally and each of said halves including top, middle, and bottom sections, the said top sections being adapted to swing inwardly alone to admit grain in loading, and the bottom sections being adapted to open edgewise when the car is full of grain independently of the other sections to discharge grain, the said bottom sections being free of said hinge mounting connections.

Signed at Chicago this 6th day of September, 1924.

HENRY BANG.
